UNITED STATES PATENT OFFICE.

JAMES H. SAGER, OF ROCHESTER, NEW YORK, ASSIGNOR TO J. H. SAGER COMPANY, OF ROCHESTER, NEW YORK.

SPRING ATTACHMENT FOR VEHICLES.

No. 851,609.

Specification of Letters Patent.

Patented April 23, 1907.

Application filed December 29, 1906. Serial No. 350,000.

To all whom it may concern:

Be it known that I, JAMES H. SAGER, of Rochester, in the county of Monroe and State of New York, have invented a new and useful Improvement in Spring Attachments for Vehicles, which improvement is fully set forth in the following specification and shown in the accompanying drawings.

My invention relates to springs and coacting means for the easy-carrying of the bodies of passenger vehicles generally, it being designed more particularly for use upon automobiles in combination with the main carrying springs and the body hangers or carrying arms. A number of these spring-attachments are employed on each automobile, one at the overhanging end of each body hanger, each attachment comprising a vertical branched hanger connected in two places with the associated main carrying spring of the vehicle body and carrying axially within it a spiral spring indirectly connected with and acting against the end of the adjacent body hanger of the vehicle.

One object of this invention, among others, is to connect each spring-attachment at two points upon or with the coacting main carrying spring of the vehicle, one connection being at the end of said main spring, to the end that the said attachment may be securely supported and held at all times in substantially a vertical position.

Another object of the invention is to provide a spring-attachment constructed and arranged so as to be readily and conveniently adapted to receive upon it any of the various forms and constructions of body hangers in use upon automobiles.

Other objects and advantages of the invention will be brought out and made to appear in the following description, and the novel features more particularly pointed out in the appended claims, reference being had to the accompanying drawings which, with the reference characters marked thereon, form a part of this specification.

Figure 1 is a side elevation of the invention and associated parts, connected as in use. Fig. 2 is a rear elevation, seen as indicated by arrow *a* in Fig. 1. Fig. 3 is a plan of the invention and associated parts. Fig. 4 is a plan of the clip or rest for the body hanger, detached. Fig. 5 is an end view of a branch holder for the spring hanger, detached, seen

as indicated by arrow *b* in Fig. 1. Fig. 6 is a transverse section of the spring hanger and associated parts taken on the dotted line *d* in Fig. 1. Fig. 7 is a central vertical section of the clip or rest for the body hanger, and associated parts, taken on the dotted line *c* in Fig. 3. Fig. 8 is a side elevation of the upper end of one branch of the spring hanger, viewed as in Fig. 1, the coupling-bolt being transversely sectioned. Fig. 9 is a side elevation of lower parts of the spring hanger and associated parts, seen as indicated by arrow *e* in Fig. 6, parts being centrally vertically sectioned. Figs. 10 and 11 are side elevations of parts showing slight modifications in the form of the body hangers. Fig. 12 is a plan of a short holder for the spring hanger, and some associated parts. Figs. 1, 2, 3, 6, 10, 11 and 12 are drawn to a scale about one-half size, the remaining figures being drawn substantially full size.

Referring to the parts shown, 1, Figs. 1, 2 and 3, is the rear end portion of the rear left body hanger of an automobile, and 2 the rear end portion of the adjacent main carrying spring for the body. 3 is a U-shape or branched hanger pending from the horizontal coupling bolt 4 at the extreme end of the main carrying spring 2, the two branches of this hanger being disposed one forward of the other, alternated and in parallel planes, as clearly shown in Figs. 1 and 3, the tie-portion 23, for the branches at their lower ends extending obliquely or diagonally from one to the other, as appears in Fig. 6. The two branches of the hanger are equal, with their upper ends bent or curled to form eyelets 22, one being clearly shown in Fig. 8. The upper portion of the forward branch is curved backward toward a middle transverse line of the hanger and the corresponding portion of the rear branch is similarly curved forward toward said middle line bringing the two eyelets 22 opposite each other and concentric with said line, as appears in Figs. 1, 2 and 3. The distance between the branches of the hanger, measured along said middle line, is equal to the width of the main spring 2, the latter and the hanger being assembled so that the eyelets 22 are adjacent to the ends of and coaxial with the loop 24 of the main spring, the coupling bolt 4 passing through all.

The hanger 3 is formed at its lower end or tie-portion 23 with an upwardly-projecting

axial threaded stud or pin 5, Figs. 2, 6 and 9, receiving upon it the lower coil of a vertical spiral spring 6, preferably of the barrel form. This spring 6 is secured in place by a nut 7 threaded on the stud 5, by means of which said spring is held normally in substantially a vertical position and axially in the hanger 3. A clip 8, Figs. 1, 2, 4 and 7, is mounted upon the upper end of the spring 6 and secured by a short vertical bolt 9 passing through the upper coil of the spring, with a clamping nut 10 at its lower end. With this hanger 3 is employed a connecting arm or connector extending from and beneath the body of the main spring 2 at a point distant from the coupling bolt 4, and engaging the hanger. One form of the connecting arm or connector is shown at 13, Figs. 1, 2, 5 and 6, another form being shown at 21, Figs. 10 and 12. The longer connector 13, when employed, has its lower end joined to the lower end of the hanger 3 by being pierced by the stud 5, as clearly shown in Fig. 9, the opening for the stud being shown at 19, Fig. 5. The short connector 21 engages the body of the hanger above the middle, as appears in Fig. 10, and this form is usually preferred as it is more simple and much more easily put to place on the main spring and the hanger or removed therefrom. These connectors are metal and, acting with the connected ends of the springs 2, serve to hold the hangers steadily in substantially vertical positions, as above stated and fully shown. The connectors, which ever form may be used, are conveniently secured to the bodies of the main carrying springs 2 by simple cross clips 14 and clamping bolts 15, Figs. 1, 3, 5 and 10, at the edges of the springs 2, as shown.

In applying this invention to an automobile one device is secured at the free end of each of the main carrying springs 2, as above described, the ends of the associated body hangers 1, formed with cylindrical heads 11, Figs. 2 and 7, being inserted between the upturned jaws of the respective clips 8, as shown in Figs. 1, 2 and 3, the coupling bolts 12 being passed through said jaws and the heads 11. The clips 8 constitute rests or bearings for the ends of the body hangers 1, as stated, and they have free vertical motions in the hangers 3 as the springs 6 contract and recover under the varying downward pressures upon them by the body hangers. And these clips 8, in addition to having vertical motions, are free to sway or swing laterally away from the axial lines of the respective hangers 3, as the main springs 2 change their forms under varying stresses brought upon them and so cause the hangers 3 to moderately shift their positions relative with the connected ends of the body hangers 1.

The pendent hangers 3 are purposely formed with alternated branches, one for-

ward of the other as stated, this construction giving breadth of space or room for the bulged minor springs 6. This will be clearly understood by inspecting the two elevations shown in Figs. 1 and 2, also the showing in Fig. 3. These springs 6 are expanded at the middle and designed to be more flexible and sensitive than the firm plate-springs 2, and receive, primarily, the downward thrusts of the body hangers 1. These spring-attachments when employed upon automobiles add materially to the comfort and pleasure of the occupants as, by means of them, the weight of the body and its load are continually and at all times resting upon springs more sensitive than the relatively inert and more slowly acting plate springs commonly used.

It is obvious that the particular form or bend of the body hangers 1 is not essential in using this invention, as any of the various forms in use, or that might suggest themselves to one skilled in the art, may be employed with these attachments, this being one of the essential objects in producing the invention. In Figs. 1, 2 and 3, is shown, for example and to illustrate this matter, a rearwardly tapering arm or body hanger 1 bent both downwardly and laterally outward to connect with the clip 8.

In Fig. 10 the body hanger or arm 16 is shown with a single downward curve at its end and attached to the clip 8 at one side by means of a pin 17 rigid in the body hanger and passing laterally through the upturned parts of the clip.

In Fig. 11 the body hanger 18 is central over the plate spring 2 and the pendent hanger 3, and formed with a long downward bend 20 to carry the body hanger high above the spring 2 so as not to touch it or the pendent hanger 3 at times when the initial spring 6 becomes momentarily materially depressed on account of some sudden action of the vehicle.

What I claim as my invention and desire to secure by Letters Patent is:—

1. A spring-attachment for vehicles, comprising a hanger pending from a main spring of the vehicle, a minor spring with vertical action within said pendent hanger, a rest upon the minor spring for the body hanger of the vehicle and means for holding the hanger steadily in vertical position.

2. A spring-attachment for vehicles, consisting of a hanger pending from a main spring, a minor spring carried by the pendent hanger, and a rest held by the minor spring for the body hanger of the vehicle, there being a connector for the body of the pendent hanger and the body portion of the main spring.

3. In a spring-attachment for vehicles, a hanger pending from the end of a main spring, a vertically-acting spiral spring rigidly joined to the pendent hanger and co-

- axial therewith, a rest on the spiral spring for the body hanger of the vehicle, the pendent hanger being connected with and controlled from two parts of the main spring.
- 5 4. In a spring-attachment for vehicles, a pendent hanger with branches connected at the opposite edges of the main supporting spring of the vehicle, a minor spring held between the branches of the pendent hanger, a 10 rest on the minor spring for the body hanger of the vehicle, and means extending from the main spring for controlling the lower end of the pendent hanger.
5. A spring-attachment for vehicles, consisting of a U-shape hanger pending from a main spring of the vehicle, a stud projecting upwardly from the bottom of said hanger midway of its branches, a spiral spring secured upon the stud, a connector for the 15 main spring and the pendent hanger pierced by the stud.
6. A spring-attachment for vehicles, comprising a hanger formed with alternated branches and having opposing eyelets at the 20 sides of the main supporting spring of the vehicle, means for connecting said hanger and said main supporting spring and an additional connection between said hanger and main spring.
- 25 7. An attachment for vehicles, comprising a hanger having oppositely curved branches with eyelets at their free ends in a line trans-

verse of the hanger, one branch being forward of the other, and the branches being joined by a diagonal portion, and a spring in 35 the hanger with a rest for the body hanger of the vehicle.

8. A spring-attachment for vehicles, comprising a hanger held by a main carrying spring of the vehicle and having branches in 40 parallel planes joined obliquely at the bottom, the free ends of said branches being bent toward a middle transverse line, with eyelets concentric with said line, and a carrying spring in said hanger for a body hanger of the 45 vehicle.

9. An attachment for vehicles, consisting of a hanger pending from a main spring of the vehicle, and formed with a pair of equal 50 oppositely turned branches in parallel planes joined at their lower ends by a portion disposed obliquely between them, opposing eyelets at the upper ends of the branches, the latter being spaced equal to the width of the said main spring, and a minor spring in the 55 hanger.

In witness whereof, I have hereunto set my hand this 27th day of December, 1906, in the presence of two subscribing witnesses.

JAMES H. SAGER.
